NONRUN KNITTED FABRIC AND METHOD
OF PRODUCING ITJohannes Paul Ludwig, Milwaukee, Wis., assign-
or to Phoenix Hosiery Company, Milwaukee,
Wis., a corporation of Wisconsin

Application October 25, 1939, Serial No. 301,097

17 Claims. (Cl. 66—198)

This invention has reference to nonrun knitted fabric. More specifically, it is concerned with nonrun weft knitted fabrics useful in connection with stockings and the like, and to methods of producing such fabrics.

My invention has for its chief aims to render weft knitted fabrics of the kind referred to proof against wale-wise running in the event of loop rupture at any point, and to secure this desideratum without distortion such as would detract from the appearance of the fabrics, and without materially affecting their elasticity—or other desirable characteristics such as resistance to snagging, strength, etc.

One way in which the foregoing and other advantages may be readily realized in practice, will appear from the following detailed description of the attached drawings, wherein Fig. I is a fragmentary diagrammatic view showing one face of nonrun knitted fabric conveniently embodying my invention.

Fig. II is a similar view showing the opposite face of the fabric.

Figs. III—XII are detail views illustrating successive steps in the production of the fabric, Figs. III, VI, IX and XI being perspective views, Figs. IV, V and VII fragmentary views in elevation and Figs. VIII, X and XII plan views.

From Figs. I and II of these illustrations, it will be observed that my improved nonrun fabric is characterized by having, at intervals lengthwise thereof, courses 1 containing lock stitches 2, and by having plain loop courses 3 and 4 intervening said lock stitch courses. In each of the lock stitches 2 of the courses 1, a twisted bight 5 formed in one side leg of a loop 6 in one wale is crossed over the other leg of such loop and also across an adjacent sinker wale loop 7, and doubled with a plain loop 8 of a neighboring wale in the same course. It will be further noted from Figs. I and II, that in each course 1, a pair of plain loops 9, 10 intervene between each pair of the lock stitches 2, and moreover that the lock stitches in one lock stitch course 1 are staggered relative to lock stitches in the next lock stitch course throughout the fabric. Accordingly, by virtue of such disposal and since each lock stitch involves a pair of adjacent loops 6 and 8, a lock stitch in one course 1 protects the two wales containing the two plain loops 9 and 10 between a pair of the lock stitches in the next lock stitch course, with the result that the fabric is well protected against running throughout its width. By interposition of two plain courses 3 and 4 between each pair of the lock stitch courses 1 and

by staggering the lock switches 2 as explained, a symmetrical disposal of said lock stitches is had by which the appearance of the fabric is greatly enhanced. If desired, however, the lock stitches may, within the scope of my invention, be arranged otherwise than shown and the number of plain courses between the lock stitch courses increased or decreased as may be found convenient or desirable in practice.

The fabric may be readily produced on a flat knitting machine of the "cotton" type after the manner shown in Figs. II—X, having a series of needles N, sinkers S, knock overs K, and an end-wise shiftable point bar (not illustrated) with special grooved loop transfer points P, which are spaced by a distance of five needles and arranged to cooperate with individual needles. As shown, the points P, are of a type in which a portion of one of the side walls of the groove is omitted to enable lateral transfer of half loops in the manner presently explained. In forming a lock stitch course 1 according to my invention, the needles N are actuated to first produce a row of plain loops as in Fig. III, whereupon the points P are lowered and the needles bodily moved inward so that definite needles N' are brought into engagement with said points without closing of the needle beards. After such engagement, the points and the needles are lowered together as shown in Fig. IV and the tips of the points thus passed into the loops held on the shanks of the engaged needles N'. As the descent of the needles N' and the points P continues, the needle beards move over the loops 6 held on said needles as said points enter further into the loops 6. This condition is shown in Figs. V and VI. As the needles descend still further from the position of Fig. VI, the loops 6 are caught in the needle beards as shown in Fig. VII. In the next step, the needles are retracted from the points as in Figs. VIII and IX, incident to which bights 5 are drawn from the left hand side legs of the loops 6 held on the needles N'. The points P are then elevated and moved to the right by the distance of one needle as shown in Figs. X and XI. At this stage of the operation, the needles are low and hold the loops 6, while the bights 5 of said loops engaged by the points P are elevated above the needles. Accordingly, as the points P are shifted rightward as above explained, the portions 11 of the engaged loops 6 will be swung over the tops of the needles N' as shown in Fig. X. Thereupon, the needles are again moved toward the points with attendant engagement now of the needles N' (adjacent the needles

N') with said points. In this movement, due to the disalignment of the needles N² with respect to the other needles as exemplified in Fig. XII, the bights 5 of the loops 6 engaged by the points 5 are turned rearward over the tops of the needles N' with resultant formation of the twists therein as shown in Fig. XII. The needles are then elevated together with the points and in such movement the needles N² pass up through the 10 twisted bights 5 of the loops 6, whereby said bights are doubled with the loops 8 already on the needles N² to complete the lock stitches, after which two plain loop courses are knitted in succession upon the needles. This cycle is repeated 15 over and over again, except that in order to stagger the lock stitches, the field of operation of the points is transposed by the extent of two needles either to the right or left as desired.

It is of course to be understood that my improved fabric may be produced equally as readily 20 by transferring leftward instead of rightward as above described by way of example, in which case the points employed would have their right hand side walls uninterrupted and their left hand 25 side walls interrupted.

Having thus described my invention, I claim:

1. Nonrun knitted weft fabric having lock 30 stitches in each of which a bight, drawn from one side leg of a loop in one wale of the fabric, extends crosswise of the other side leg of such loop, and is doubled with a loop in another wale.

2. Nonrun knitted weft fabric having lock 35 stitches in each of which a bight, drawn from one side leg of a loop in one wale, extends crosswise of the other side leg of such loop, and is doubled with a loop in the next adjacent needle wale.

3. Nonrun knitted weft fabric, according to 40 claim 1, in which the displaced bights of the lock stitches are twisted.

4. Nonrun knitted weft fabric, according to 45 claim 2, in which the displaced bights of the lock stitches are twisted.

5. Nonrun knitted weft fabric, according to 50 claim 1, in which the lock stitches are formed in spaced courses whereof the loops are interengaged with intervening courses of plain loops.

6. Nonrun knitted weft fabric, according to 55 claim 1, in which the lock stitches occur at spaced intervals in courses whereof the loops are interengaged with loops of intervening plain courses, and in which the lock stitches of one lock stitch course are located midway between the lock stitches of another lock stitch course.

7. Nonrun knitted fabric, according to claim 1, 60 in which the displaced bights of the lock stitches are twisted, and in which the lock stitches are formed in spaced courses whereof the loops are interengaged with intervening courses of plain loops.

8. Nonrun knitted fabric, according to claim 1, 65 in which the displaced bights of the lock stitches are twisted, in which the lock stitches occur at spaced intervals in courses whereof the loops are interengaged with loops of intervening plain courses, and in which the lock stitches of alternate lock stitch courses are located midway between the lock stitches of the other lock stitch courses.

9. Nonrun knitted fabric, according to claim 2, 70 in which the displaced bights of the lock stitches are twisted, and in which the lock stitches are formed in spaced courses whereof the loops are interengaged with intervening courses of plain loops.

10. Nonrun knitted fabric, according to claim 2, 5 in which the displaced bights of the lock stitches are twisted, in which the lock stitches occur in courses whereof the loops are interengaged with loops of intervening plain courses, and in which the lock stitches of alternate lock 10 stitch courses are located intermediate the lock stitches of the other lock stitch courses.

11. The method of producing nonrun knitted 15 weft fabric by repetitions of a cycle which comprises forming a course of loops on a row of needles, displacing bights drawn from side legs of individual loops at intervals along the series laterally across the other legs of such loops and doubling said bights with loops on other needles, 20 and then knitting one or more plain courses on the needles.

12. The method of producing nonrun knitted 25 weft fabric by repetitions of a cycle which comprises forming a course of loops on a row of 20 needles, displacing bights drawn from side legs of individual loops at intervals along the series laterally across the other legs of such loops, twisting said bights and doubling them with loops on other needles, and then knitting one or 30 more plain courses on the needles.

13. The method of producing nonrun knitted 35 weft fabric by repetitions of a cycle which comprises forming a course of loops on a row of needles, displacing bights drawn from side legs 40 of individual loops at intervals along the series laterally across the other legs of such loops, and across the contiguous sinker wale loops, and doubling said bights with loops on the immediately adjacent needles, and then knitting one or 45 more plain courses on the needles.

14. The method of producing nonrun knitted 50 weft fabric by repetitions of a cycle which comprises forming a course of loops on a row of needles, displacing bights drawn from side legs of individual loops at intervals along the series laterally across the other legs of such loops and doubling said bights with loops on other needles 55 to form lock stitches, knitting one or more plain courses on the needles, knitting another lock stitch course as before but forming the lock stitches on needles intermediate those previously used for this purpose, and then again knitting one or more plain courses.

15. The method of producing nonrun knitted 60 weft fabric by repetitions of a cycle which comprises forming a course of loops on a row of needles, displacing bights drawn from side legs of individual loops at intervals along the series laterally across the other legs of such loops, twisting said bights and doubling them with loops on other needles to form lock stitches, knitting one or more plain courses on the needles, knitting another lock stitch course as before but forming the lock stitches on needles intermediate 65 those previously used for the purpose, and then again knitting one or more plain courses.

16. The method of producing nonrun knitted 70 weft fabric by repetitions of a cycle which comprises forming a course of loops on a row of needles, displacing bights drawn from side legs of individual loops at intervals along the series laterally across the other legs of such loops and across the contiguous sinker wale loops and doubling said bights with loops on the immediately adjacent needles to form lock stitches, knitting one or more plain courses on the needles, knitting another lock stitch course as before, but forming the lock stitches on needles intermediate 75 those previously employed for the pur-

pose, and then again knitting one or more plain courses.

5 17. The method of producing nonrun knitted weft fabric by repetitions of a cycle which comprises forming a course of loops on a row of needles, displacing bights drawn from side legs of individual loops at intervals along the series laterally across the other legs of such loops and across the contiguous sinker wale loops, twisting

said bights and doubling them with loops on the immediately adjacent needles to form lock stitches, knitting one or more plain courses on the needles, knitting another lock stitch course as before, but forming the lock stitches on needles intermediate those previously employed for the purpose, and then again knitting one or more plain courses.

JOHANNES PAUL LUDWIG.
